UNITED STATES PATENT OFFICE

115,501

DESIGN FOR AN OZONE MACHINE

John E. Kenney, Portland, Oreg.

Application May 6, 1939, Serial No. 84,834

Term of patent 7 years

To all whom it may concern:

Be it known that I, John E. Kenney, a citizen of the United States, residing at Portland, in the county of Multnomah and State of Oregon, have invented a new, original, and ornamental Design for Ozone Machines, of which the following is a specification, reference being had to the accompanying drawing, forming part thereof.

Figure 1 is a perspective view of the ozone machine, showing my new design; and

Figure 2 is a side elevational view thereof.

I claim:

The ornamental design for an ozone machine, as shown.

JOHN E. KENNEY.
